CLAIM

The ornamental design for an animal automobile seat, as shown and described.

DESCRIPTION

FIG. 1 is a perspective view of the first embodiment of the animal automobile seat showing my new design. The broken lines show the environment and do not form a part of the design of the claimed invention.

FIG. 2 is a front end view of the animal automobile seat; FIG. 3 is a side view of the animal automobile seat, the opposite side thereof being identical thereto;

FIG. 4 is a rear end view of the animal automobile seat; FIG. 5 is a top view of the animal automobile seat; and, FIG. 6 is a perspective view of the second embodiment of the animal automobile seat, including an animal retention strap. The animal shown in broken lines is included to show the retention strap in use and does not form a part of the design of the claimed invention.

The animal shown in broken lines is included to show the retention strap in use and does not form a part of the design of the claimed invention.

The fragmented depiction of the fabric-like pattern shown on the backrest, armrests, and the seat pads in FIGS. 1 through 6 is understood to be continuous throughout.
